UNITED STATES PATENT OFFICE.

ANNIE W. STIMSON, OF LOS ANGELES, CALIFORNIA.

NEEDLE.

SPECIFICATION forming part of Letters Patent No. 727,020, dated May 5, 1903.

Application filed November 26, 1902. Serial No. 132,937. (No model.)

To all whom it may concern:

Be it known that I, ANNIE W. STIMSON, of Los Angeles, in the county of Los Angeles and State of California, have invented certain new and useful Improvements in Needles; and I do hereby declare the following to be a full, clear, and exact description of the invention, such as will enable others skilled in the art to which it appertains to make and use the same.

10 My invention relates to an improvement in needles, and more particularly to such as are employed for feeding a ribbon or tape through beading, a pocket, or a series of pockets, the object of the invention being to so construct

15 a needle of the class above mentioned as to facilitate the ready attachment of ribbon thereto and prevent the engagement or entanglement of the fastening means with the beading or pockets through which the ribbon is to be fed.

A further object is to provide a ribbon-needle which shall be simple in construction, cheap to manufacture, easy to manipulate, and which shall effectually perform all the

25 functions required of such a needle.

With these objects in view my invention consists in certain novel features of construction and combinations of parts, as will be hereinafter more fully described, and pointed out

30 in the claims.

In the accompanying drawings, Figure 1 represents a view of the needle-blank. Fig. 2 is a view of same bent into shape ready for use. Fig. 3 is a view in section. Fig. 4 is a

35 view of a piece of beading in which the ribbon and needle are inserted, and Fig. 5 is a section of the blank on line $x-x$ of Fig. 1.

1 represents the blank, constructed of any suitable material, preferably of metal, from

40 which the needle is formed. To form the needle from the blank, the latter is bent at 3 to form end section 2, while end section 5 is formed by bending the blank at 6, the central section 4 constituting the body of the needle.

45 End section 2 is provided with a pointed end for piercing the ribbon or tape to be threaded and is preferably made tapering from end to end, so as to permit of its entire passage

through the body portion of the narrowest widths of ribbon or tape. End section 5 is 50 of sufficient length to overlap the pointed end of section 2 and prevent the latter from engaging the material while the ribbon or tape is being threaded through the same. Central section 4 and end section 5 are so shaped with 55 respect to one another that when the latter is bent to its normal position its outer edges aline with the corresponding outer edges of the former and the needle will have a tapering shape.

60 As previously stated, end section 5 is bent at the point 6, which latter becomes the point of the needle, and owing to its rounded form its insertion through the fabric is rendered exceedingly easy and all danger of injury 65 thereto by hooking into the material, as would be the case were the point made of a single thickness of material, is avoided.

The side edges of the entire needle are rounded to prevent its cutting the lace or 70 other material.

The device described is exceedingly simple in construction, cheap to manufacture, and is capable of being quickly attached to the end of a piece of ribbon, tape, or the like, it 75 simply being necessary to move section 5 outwardly a distance sufficient to permit section 2 to be passed through the end of the material to be threaded, after which sections 2 and 5 are returned to their normal positions and 80 the needle is then ready for use, with section 5 overlapping the pointed section 2 and effectually preventing the latter from in any way engaging the lace or other material through which the ribbon or tape is being threaded. 85

Having fully described my invention, what I claim as new, and desire to secure by Letters Patent, is—

1. A tape or ribbon needle, made in a single piece, and comprising three integral members, one of which is pointed, and one of said members overlapping the end of the pointed member.

2. A tape or ribbon needle, comprising a central member and two end members disposed upon the central member, one of said

end members being pointed and projecting under the other end member.

3. A tape or ribbon needle consisting of a single flat strip having one end pointed, said strip bent upon itself at two points and the free ends overlapping.

In testimony whereof I have signed this

specification in the presence of two subscribing witnesses.

ANNIE W. STIMSON.
